UNITED STATES PATENT OFFICE.

HARRY BUXTON HARTMAN, OF SCOTTDALE, PENNSYLVANIA, ASSIGNOR TO ELECTRIC WATER STERILIZER AND OZONE COMPANY, A CORPORATION OF PENNSYLVANIA.

FLUID-PRESSURE-ACTUATED SWITCH VALVE.

Application filed August 13, 1920. Serial No. 403,431.

To all whom it may concern:

Be it known that I, HARRY B. HARTMAN, citizen of the United States, residing at Scottdale, in the county of Westmoreland and State of Pennsylvania, have invented certain new and useful Improvements in Fluid-Pressure-Actuated Switch Valves, of which the following is a specification.

This invention relates to the general subject of valves and has particular reference to an improvement in devices of the type that are responsive to differential fluid pressure conditions.

A primary object of the invention is to provide a valve for automatically opening and closing an electrical circuit through the medium of a switch which should be opened and closed according to pressure conditions in a water supply line such for instance as the main feed line of a water purifying apparatus, of the type disclosed in my copending application Serial No. 353,857 filed January 24, 1920. That is to say, it is proposed to provide a valve that will maintain the switch closed to supply electrical current to the apparatus when the proper water pressure is in the supply line, but which in event that the water supply is cut off, will cause the switch to open to prevent the operation of devices otherwise caused to function by the electrical current supplied through the switch line.

A further and more specific object of the invention is to provide a valve of simple and practical construction, and in addition to being susceptible of adjustment to meet varying pressures in the supply line, is thoroughly leak proof and so designed as to reliably function under all conditions of use.

With the above and other objects in view which will become apparent as the description proceeds, the invention preferably consists in the novel construction, combination, and arrangement of parts hereinafter more fully described, illustrated and claimed.

A preferred and practical embodiment of the invention is shown in the accompanying drawings, in which:—

Figure 1 is a vertical sectional view of the valve, the dotted lines showing the position of the plunger and plunger stem when the switch is closed.

Figure 2 is a horizontal cross section on the line 2—2 of Figure 1.

Figure 3 is a horizontal cross section on the line 3—3 of Figure 1.

Similar reference numerals designate corresponding parts throughout the several figures of the drawings.

In its preferred embodiment the present valve device includes in its organization a suitable valve casing 1 which is open at one end as at 2 while the other end is closed as at 3. The said closed end is formed with an interiorly threaded collar 4 and cooperates with the sides of the casing to provide a plunger chamber 5, for receiving a plunger 6 designed to have a leak proof fit therein. This plunger preferably consists of the metallic body plate 7 and the leather cup 8 that is held in place by the clamping nut N and whose relatively free skirt portion 8' hydraulically seals itself against the sides of the chamber 5 to prevent the escape of liquid at this point.

The said plunger 6, comprising the body plate 7 and nut N is carried upon a stem 9 one end of which projects exteriorly of the casing to perform the function of a switch operating member. That is to say, the stem 9 is provided with threads 10 for receiving the threaded boss 11 of the body plate 7 and a similar portion 12 of the nut N in such a manner that the leather cup 8 may be securely locked or held in a fixed position on the stem.

For the purpose of guiding the stem 9 in its movement to effect the operation of the switch, and also to perform the more important function of regulating the pressure for seating the plunger 6, a relatively adjustable bushing 13 and spring 14 are provided. That is to say, the upper end of the casing 1 is fitted with a threaded bushing 13 whose central bore acts as a guide for the stem 9 while its lower end constitutes an adjustable abutment for tensioning the spring 14 surrounding the stem 9 and engaging with the body plate 7 about the boss 11 thereof. By reason of the threaded engagement of the bushing 13 with the casing it will be apparent that the tension of the spring 14 may be readily adjusted to meet varying pressures in the supply line.

For example, if

- the pressure in the supply line is 75 pounds, of an air compressor space above the back pressure on the plunger would be very much greater than if the initial pressure were 50 pounds, and, to meet the former condition, the bushing 13 may be screwed down to compress the spring and thus exert more pressure on the back of the plunger in the direction of seating, while on the other hand if the initial pressure in the supply line is 50 pounds the back pressure on the plunger would be lower, and the bushing 13 may be then screwed upwardly to release some of the compression in the spring. This feature of the valve is important since it enables the same to be used on supply lines carrying different pressures, so that by setting the tension of the spring to meet the pressure the valve may be caused to reliably actuate the switch.
- 20 The end 9^b of the stem 9 preferably has a guiding engagement in the central opening 15 of the spider 16 formed within the body of the fitting 17 which is interiorly threaded as at 18 to engage with the corresponding threads on the exterior of the casing 1. The fitting 17 in addition to providing a guide for the lower end of the plunger stem 9 is also provided with a nipple portion 19 for fitting directly to the supply line S so that the full pressure of water or other liquid within the line S is exposed directly to the side of the plunger 6 having the leather cup 8 fitted thereto. Obviously when pressure exists to a sufficient degree in the line S the plunger 6 will be elevated, and on the other hand when the pressure drops below the predetermined point the spring 14 will seat the plunger and retract the stem 9.
- 25 The collar portion 4 of the casing 1 may be conveniently utilized for supporting the frame F of the electrical switch mechanism arranged within the casing 20. This switch mechanism may be of any standard and well known type that includes an operating stem 21 which when pushed in one direction closes the electrical circuit, and upon the release of such pressure automatically opens the circuit. With this arrangement, as long as sufficient pressure exists in the supply line S to elevate the plunger 6 the stem 9 thereof will be positively projected to maintain the switch mechanism closed, but upon the fall of pressure in the line S the switch will be opened automatically due to the retraction 30 of the stem 9 within the casing, in the manner previously indicated.
- 35 For the purpose of relieving the underside 22 of the switch casing 20 of the heavy pressure imposed thereon when the plunger 6 is elevated, a suitable stop abutment 1^a may be placed or formed within the chamber 1 to engage the back of the body plate 7 as shown in Figure 1. Also, to insure the free operation of the plunger under the influence of the spring 14, and prevent the formation
- 40 of an air compressor space above the plunger, the casing 1 may be provided with an air vent 1^b.
- 45 By reason of the novel detachable mounting of the switch frame F upon the collar 4 of the casing it is possible to readily detach the switch mechanism from the valve for adjustment or repair while at the same time it will also be apparent that the body of the valve 1 and the fitting 17 may be readily separated to have access to the plunger chamber and plunger operating therein. Also the provision of the leather cup 8 is of material importance since water pressure on the skirt portion 8^a thereof will produce a tight fit with the sides of the body 1 to thereby increase the sealing effect between the plunger and casing and obtain a thoroughly practical and leak proof valve which is highly desirable, and in fact essential to a satisfactory installation.
- 50 In connection with the switch frame F it will also be noted that the same has a relatively swivelled engagement with the valve body. That is to say, the arms F' of the frame have the web F² which connects the same, so formed as to fit over the tubular collar whereby the frame may be adjusted circumferentially thereabout to enable the wires of the switch to be led off at any convenient point to go directly to the electrical devices. To enable the frame to be secured in the desired adjusted position suitable fastenings F⁴ such as set screws or the like may be employed.
- 55 From the foregoing it is believed that the features and advantages of the present type of valve will be readily apparent and it will of course be understood that changes, in the form, and proportion of parts may be readily resorted to without departing from the spirit of the invention or scope of the appended claims.
- 60 I claim:—
1. In an electro-fluid device of the class described, a casing having a relatively closed end wall provided with a collar and open at the other end, a chambered fitting secured to the open end of the casing and provided with a threaded pipe-nipple-receiving opening, an abutment carried by the inside wall of the casing, a plunger operable in the casing, a spring for holding said plunger normally seated against a portion of said fitting, a bushing arranged within said collar and providing a guide for the stem of the plunger and also constituting an abutment for said spring, and a switch device surmounting said casing and surrounding the collar.
- 65 2. In an electro-fluid device of the class described, a plunger casing having a relatively closed end and open at the other end, a chambered fitting secured to the open end of the casing and having an interiorly

threaded pipe-nipple-receiving portion, said fitting also having a spider formed in the chambered portion thereof and provided with a guide opening, a plunger operable within the casing, a stem for adjustably carrying said plunger and extending to opposite sides thereof, the stem at one side of the plunger operating in said guide open-

ing of the spider and the stem at the other side of the plunger being guided in the relatively closed end wall of the casing, and a switch surmounting said casing and operated by said plunger stem. 10

In testimony whereof I hereunto affix my signature:

HARRY BUXTON HARTMAN.
